US0D1067230S

(12) **United States Design Patent** (10) **Patent No.:** **US D1,067,230 S**
(45) **Date of Patent:** **** Mar. 18, 2025**

(54) **FINGERPRINT READER**

(71) Applicant: **Bird Home Automation GmbH**, Berlin (DE)

(72) Inventor: **Sascha Keller**, Berlin (DE)

(73) Assignee: **Bird Home Automation GmbH**, Berlin (DE)

(**) Term: **15 Years**

(21) Appl. No.: **29/815,158**

(22) Filed: **Nov. 11, 2021**

(30) **Foreign Application Priority Data**

May 18, 2021 (EM) 008543631-0001

(51) **LOC (15) Cl.** **14-02**

(52) **U.S. Cl.**

USPC **D14/384**

(58) **Field of Classification Search**

USPC D14/384, 383, 342, 407
CPC G06F 21/32; G06F 21/33; G06F 21/34;
G06F 21/35; G06F 21/316

See application file for complete search history.

(74) Attorney, Agent, or Firm — Young Basile Hanlon & MacFarlane, P.C.

(57) **CLAIM**

The ornamental design for a fingerprint reader, as shown and described.

DESCRIPTION

FIG. 1 is a front, left perspective view of a fingerprint reader showing my new design.

FIG. 2 is a rear, right perspective view thereof.

FIG. 3 is a front plan view thereof.

FIG. 4 is a rear plan view thereof.

FIG. 5 is a left side view thereof.

FIG. 6 is a right side view thereof.

FIG. 7 is a top plan view thereof.

FIG. 8 is a bottom plan view thereof; and,

FIG. 9 is an environmental view, showing the fingerprint reader as it exists in an IP Access Control Device, shown in broken line.

Broken lines of equal length (e.g., dash-dash) represent unclaimed subject matter and form no part of the claimed design.

1 Claim, 8 Drawing Sheets
